No. 755,181.

PATENTED MAR. 22, 1904.

J. E. SMITH.
TOILET APPLIANCE.
APPLICATION FILED JULY 16, 1903.

NO MODEL.

UNITED STATES PATENT OFFICE.

JOHN E. SMITH, OF ETNA, PENNSYLVANIA.

TOILET APPLIANCE.

SPECIFICATION forming part of Letters Patent No. 755,181, dated March 22, 1904.

Application filed July 16, 1903. Serial No. 165,824. (No model.)

To all whom it may concern:

Be it known that I, JOHN E. SMITH, a citizen of the United States, residing at Etna, in the county of Allegheny and State of Pennsylvania, have invented a new and useful Toilet Appliance, of which the following is a specification.

My invention is an improvement in toilet appliances, and comprises means for temporarily holding a towel and a folding case pivotally secured to the towel-rack, the said case containing a mirror, brush and comb, and a pin-cushion, the various parts of the casing being adapted to fold upon themselves and the folded casing to in turn fold back upon the towel-rack.

The object of my invention is to produce a compact device of this character requiring but little room.

My invention consists in the novel features of construction and combination of parts described hereinafter, particularly pointed out in the claims, and shown in the accompanying drawings, in which—

Figure 1 is a perspective view showing my complete device, the various parts being arranged in position for use. Fig. 2 is a front elevation showing the parts folded. Fig. 3 is a perspective view of the toilet-case folded.

Fig. 4 is a perspective view of one of the journal-boxes carried by the towel-rack. Fig. 5 is a detail view, partly in section, showing means for removably journaling an end of the towel-roller. Fig. 6 is a longitudinal section through the towel-rack, the roller being in elevation and the upper portion of the sectional journal-block being removed.

In the construction of the appliance illustrated in these drawings, A represents the base-plate of a rack adapted to rest against and be secured to a wall by suitable screws. Secured to this base and adjacent one end of same is a sectional journal-box B, each section being recessed, as shown at B', receiving the spherical head C' of the roller C. The roller has flanges C² adjacent each end, the ends being reduced, one end carrying the ball C'. The opposite reduced end C³ is journaled in a block B². This block has a vertical slot B³ extending downward from its upper edge, curved

at the bottom to accommodate the rotatable roller end, the upper portion of the slot being wider than the lower portion, and the sides of the slot being notched, as at B⁴.

Springs B⁵ are secured to the upper edge of the block B², one on each side of the slot, and extend downward into the slot, their lower free ends bearing on and holding the roller end in place. By pressing the ends of these springs into the notches the end C³ of the roller can be lifted between them and removed from the block. An arm D is pivoted at one end to the base A and at the other end is rigidly secured to the back of a frame E, which frame carries on its opposite face a mirror E'. Hinged to this frame is a box or tray E², adapted to hold a comb and brush. The tray E² is preferably hinged to the lower edge of the frame, and a second frame, E³, is hinged to one side of the frame E². A hook E⁴ engages an eye E⁵ on the frame E and supports the tray in a horizontal position when the case is open, and a hook E⁶ engages an eye E⁶ on the side of the frame when the tray is folded to close the case, which, it will be understood, comprises a tray and the two frames. A pin-cushion E⁷ is arranged on the inner side of the frame E³. The tray E² also carries hooks E⁸, which engage eyes E⁹ on frame E. A pin F is secured to the back of the frame E and is engaged by a hook F', pivoted to the base, whereby the case is steadied when opened and in use. A projection or plate E¹⁰ is secured on one side of the frame E, the said plate resting on the top of the base A when the case is folded back, as shown in Fig. 2. When not in use, the tray E² and frame E³ are folded one upon the other and both on the front of frame E and secured by the hooks E⁴ E⁶. The hook F' is disengaged and the arm D and case swung back on the base A. A towel G is placed on the roller, and when an endless towel is used it can be slipped off over the end C³ of the roller by pressing back the spring B⁵ and lifting the roller from its bearing in the block B².

Having thus fully described my invention, what I claim as new, and desire to secure by Letters Patent, is—

1. A device of the kind described comprising

a base-plate adapted to be secured to a wall, an arm pivoted to said plate, a casing secured to the arm, said arm being adapted to fold on the base-plate, a hook pivoted to the base, a pin secured to the casing adapted to be engaged by the hook when the arm is in a vertical position.

2. The combination with a base-plate adapted to be secured to a wall, of a frame having 10 a mirror on one side, a tray hinged to an edge of said frame, a second frame having a cushion on its inner face and hinged to the first-mentioned frame, the said frames being adapted to fold one upon another, means for locking the frames together when folded, and an arm pivoted at one end to the base-plate and secured at the opposite end to one of the frames, the said frames and tray when folded 15

being adapted to rest against the upper edge of the base-plate.

3. A device of the kind described comprising a base-plate, an arm pivoted to the plate, a frame secured to the non-pivoted end of the arm, a tray hinged to the lower edge of the frame and adapted to fold upward against the 20 face of the frame, and a second frame hinged to the side of the first-mentioned frame and adapted to fold over the bottom of the tray when the latter is folded against the first-mentioned frame, and means for locking the two 25 frames together when folded.

JOHN E. SMITH.
